UNITED STATES PATENT OFFICE

1,999,792

FOUNDATION GARMENT

Jessie Taylor, Indianapolis, Ind.

Application September 21, 1933, Serial No. 690,435

1 Claim. (Cl. 2-27)

The object of this invention is to provide a foundation garment which will hold up the bust in accordance with the prevailing style and which will be comfortable to the wearer in sitting and 5 stooping and all unusual positions of the body as well as in the usual positions.

The object also is to provide an elastic abdomen support which will reduce the accumulation of fat without uncomfortable pressure or 10 other discomfort and which can be adjusted for figure improvement.

A further object is to provide a foundation garment which will be easy for the wearer to put on and take off without assistance and which when 15 worn will hold the body in a constant graceful and healthy position.

A further object is to provide a foundation garment with shoulder straps which will remain in correct position on the shoulders and which will 20 hold the straps of other garments in place.

I accomplish the above principal objects, and other objects which will hereinafter appear, by the garment illustrated in the accompanying drawing, in which—

Fig. 1 is an inside elevation of the garment open ready to be put on the body of a wearer;

Fig. 2 is a horizontal section of the garment, removed from the body of the wearer, but in the position as it is worn, the section being 30 through that portion of the garment adapted for covering the abdomen;

Fig. 3 is an edge view of the metal clip for use on the shoulder straps for attaching the straps of other garments;

Fig. 4 is a top plan view of Fig. 3, broken away in part;

Fig. 5 is a front view of a woman wearing my improved foundation garment, and

Fig. 6 is a back view of a woman wearing the 40 garment.

Like characters of reference indicate like parts in the several views of the drawing.

The body 7 of the garment extends from close 45 under the arms of the wearer to approximately opposite the hip joints and has a split from top to bottom on one side, preferably the left side for convenience. The ends 8 and 9, thus formed, are provided with hooks and eyes, respectively, for ready and convenient uniting and separation in 50 putting on and taking off of the garment by the wearer. A seam 10 at a corresponding place on the right side defines the front of the garment, which is the portion bounded on the side by the lines 8 and 10. The upper portion of this front 55 has the usual bust covers 11, 11, and between the

latter and extending to the bottom of the body front is a panel 12 of elastic cloth.

The back of the foundation garment extends from the end 9 to the seam 10. It may be continuous but is preferably split down near the end 9 to form the ends 13 and 14. The ends 13 and 14 are provided with eyelets through which laces 15, 16 and 17 are passed for the purpose of holding the ends in more or less close relation to each other, as will hereinafter more fully appear. At 10 such frequent intervals as may be desired the front and back of the garment are provided with vertical casings 18 in which elastic stays are placed and retained. These stays may be of any suitable structure and material but they will preferably be of steel, made and attached in accordance with the instructions of Patent No. 1,854,530, issued to me April 19, 1932.

Shoulder straps 19, 19, are secured to the front and back of the garment, here shown as by 20 means of buttons but other fastenings may be used. They extend over the shoulders of the wearer in the manner shown in Figs. 5 and 6. They are formed out of elastic tape and are each provided with a metal clip 20, 20, each of which is 25 slidingly attached to its strip by passing the strip through a pair of slots 22 and 23, formed in the lower member 21 of the clip. The clip is formed out of a strap of spring metal bent U-shape to form the lower member 21 and an upper member 30 24. The ends of members 21 and 24 normally contact each other to retain the straps of other garments which are slipped between the members 21 and 24 by spreading the ends apart.

Sewed to the front of the garment on the inner 35 side near the end 9 is a cloth strip 26 having a series of eyes to be engaged by hooks, and sewed to the inside of the garment front near the seam 10 is a cloth strip 27. Fastened by sewing or otherwise, to the cloth strip 27 is an elastic all-rubber sheet 28, to the opposite edge of which rubber sheet a cloth strip 29 is fastened. The cloth strip 29 has a series of hooks, above referred to, to engage the eyes on the strip 26. As indicated in Fig. 2, the sheet or band 28 is normally shorter in horizontal length than is the front portion of the body member 7 which lies immediately in front of and between the ends of the band 28. The rear portion of the body member 7, Fig. 1, bounded by the end 9 and seam 10, 50 has a central vertically disposed elastic panel 31 inserted therein to extend from top to bottom of the member 7.

The manner of using my foundation garment is as follows: The garment being unhooked and 55

open at 8, 9, and 26, 29, the body of the garment is placed around the body of the wearer with the straps 19, 19, going over the shoulders. Then the rubber sheet 28 is brought around in front of the abdomen and its end 29 is hooked to the eyes of strip 26. Then the body front is folded against the breast and abdomen of the wearer and end 8 is hooked to end 9.

Should the laces 15, 16 and 17 be too tight 10 or not tight enough an adjustment is made in the laces to suit by the wearer herself, or this adjustment may be made by an assistant without removing the garment from the wearer.

The laces are preferably in a plurality of separate lengths 15, 16 and 17 to enable the garment to be tightened or loosened for smaller or more particular areas of the body and to take up looseness as the figure changes during the wear of the garment. Referring to the drawing, 15 particularly to Fig. 2, the sheet or band of rubber 28 is initially under greater tension on the wearer than is the panel 12. The tension on either the band 28 or panel 12, it is obvious, is transmitted through the body 1 to the rear elastic panel 31. Now when the central or intermediate lace 16 is drawn up tighter, the front elastic panel 12 is then subjected to an increased tension. As the tension on the panel 12 increases, 20 the panel 31 stretches and permits a forward travel of the body 1 therefrom so as to allow the band 28 to shrink in length and to have its relieved tension then carried by the front panel 12. This variation in tension on the band 28 through inverse variation in tension on the panel 25 12 is accomplished by adjustment of the intermediate lace 16 without disturbing the adjustments of the top and lower laces 15 and 17. This is desired since it is the abdomen which will change rather than the upper and lower portions 30 of the body of the wearer. A particular advantage of the separate individual laces is that the intermediate lace may be employed to take up 35 the garment through the central area immediately over the rubber sheet 28 so that the initial tension in that sheet may be reduced by tighter lacing of the intermediate lace. Thus it is possible to effect an adjustment of the central area 40 without changing adjustment in the upper and lower areas of the garment since the intermediate lace 16 may be adjusted independently of the 45 upper and lower laces 15 and 17.

The straps of any other clothing are then caught under the clips 19.

It will be noted that the garment is made low in the back, so as not to show when low necked gowns are worn, and a narrow gusset 31 of elastic cloth extends from top to bottom of the middle back of the garment.

Variations in structure and size of parts, some of which I have indicated, may be made within the scope of the appended claim.

I claim:

A figure supporting and reducing garment comprising a major body surrounding member made of flexible non-elastic material, said body member having a vertically disposed side opening throughout its height to be detachably closed by fasteners, upper, lower and intermediate individually controlled laces across a second vertical opening located adjacent the first opening, said series of laces providing means for independent local girth adjustments of the body member, a vertically disposed panel of elastic material interposed centrally of the back of the body member to extend from top to bottom thereof, and a like panel interposed centrally of the front of the body member, said body member being of sufficient height to extend from over the breasts of the wearer down over the hips, the upper front portion of the body member at each side of said central elastic panel being formed to receive and support the breasts; an elastic band within said body member engaging by one vertical edge with said body member at one side thereof to extend around forwardly within the member and detachably engage in non-adjustable relation by its other vertical end to the body member on its opposite side back of said first opening to extend across the abdomen of the wearer, said band being normally shorter in horizontal length than the horizontal length of the front portion of the body member between the band ends whereby the band is in initial tension greater than that of said front portion of said body member when the body member is closed at said first opening, said band tension being in opposition to that then set up in said rear panel, and said band tension being relieved by tighter lacing of said intermediate lace, said front panel being thereby subjected to increased tension to compensate for and distribute the tension otherwise on said band.

JESSIE TAYLOR.
